UNITED STATES PATENT OFFICE.

HENRY MUELLER, JR., OF ST. LOUIS, MISSOURI.

STREET-SWEEPER.

SPECIFICATION forming part of Letters Patent No. 563,869, dated July 14, 1896.

Application filed October 17, 1895. Serial No. 565,990. (No model.)

To all whom it may concern:

Be it known that I, HENRY MUELLER, Jr., a citizen of the United States, residing at St. Louis, in the State of Missouri, have invented 5 certain new and useful Improvements in Street-Sweepers, of which the following is a full, clear, and exact description, reference being had to the accompanying drawings, forming a part hereof.

My invention has relation to improvements in street-sweepers; and it consists in the novel arrangement and combination of parts, more fully set forth in the specification and pointed out in the claims.

In the drawings, Figure 1 is a side elevation of my complete invention. Fig. 2 is a rear end view of the same. Fig. 3 is a plan view of the rotating disk carrying the brushes. Fig. 4 is a section taken through the broom-spindle 20 on the line *x x* of Fig. 1. Fig. 5 is a cross-section on the line *y y* of Fig. 4, and Fig. 6 is a top plan view of a double form or modification of the sweeper.

The object of the present invention is to construct a street-sweeper which shall in every respect be a gutter-broom, that is, a broom which will thoroughly clean out the contents of gutters, and effectively sweep all the dirt that has accumulated at the juncture 30 of the curbstone and the street proper. To this end I have devised a street-sweeper which in detail may be described as follows.

Referring to the drawings, 1 represents a frame the front wheels 2 of which are merely shown in dotted lines in Fig. 1 to indicate 35 their relative position.

3 represents the rear driving-wheels, which are fixed to the ends of a shaft 4, mounted and revolving in suitable boxing 5 at the 40 bottom of the rear of the frame. At a convenient point along the shaft 4 is secured a sprocket-wheel 6, over which passes a chain 7, which operates a small sprocket-wheel 8, forming a part of the female coupling 9 of a 45 suitable clutch mechanism, said female coupling freely revolving at one end of a transverse shaft 10, mounted in suitable bearings 11 on top of the frame. The male coupling 12 of the clutch is feathered to the projecting 50 end of the shaft 10 in the usual well-known manner, and is coupled with or uncoupled from the female portion by the yoke 13 of the

short arm 14 of a shifting-lever 15, pivoted to an arm 16, carried by the frame, and held in any of the two positions by pins passed 55 through alining openings of the said lever and of a plate 17 at the end of the said arm. The driver can thus clutch or unclutch the shaft 10 from the action of the driving-wheels 3 at pleasure. The opposite end of the shaft 60 10 has secured thereto a bevel-pinion 18, which meshes with a similar pinion 19, keyed to the revolving spindle 20 of the broom 21. The feather 22, by which the pinion 19 is keyed to the spindle, is of sufficient length to allow for 65 the necessary longitudinal adjustment of the spindle through said pinion, as subsequently more particularly referred to. The pinion 19 has a tubular extension 23, which, whatever may be the relative position of the spindle, always operates within the boxing formed by a block 24, secured to the lateral beam of the frame, and the clip 24 embracing said extension and having its opposite ends secured to the inner surface of the said block, as best 75 seen in Fig. 5.

As seen from Figs. 1 and 2, the broom-spindle 20 tilts forward on the frame, being inclined not only to the general horizontal surface of the frame, but also to the general 80 plane of rotation of the wheels 3. That is to say, it inclines diagonally upward with respect to the four corners of the frame. The spindle is held rigidly in its inclined position by the supporting-bracket 25, secured to the 85 top of the frame. The lower or depending end of the spindle carries a plate or disk 26, having an inclined or bevel peripheral edge 27, along which are disposed in pairs a series of pins 28 at right angles to the surface of 90 said peripheral edge, the outer ends of the pins being screw-threaded and each pair of pins being adapted to have passed over it a retaining-plate 29, held in place by nuts 30, passed over the outer ends of the pins. Between the retaining-plates 29 and the inclined 95 peripheral edge of the disk 26 the individual brushes 31 of the broom are clamped, by which arrangement the several brushes are given a uniform outward inclination, so as to give the broom, as a whole, the form of the frustum 100 of a cone, as best seen in Fig. 1.

As the sweeping edge of the broom wears away, it becomes necessary to depress or ad-

just the broom the required distance to effect the necessary contact between said edge and the ground or surface to be swept. This is accomplished by the following mechanism: 5 Loosely embracing the upper portion of the spindle 20 is an exteriorly-screw-threaded sleeve 32, the lower portion of the sleeve working in the interiorly-screw-threaded bearing 33, forming the upper portion of the supporting-bracket 25, the sleeve retaining its relative position on the spindle by the retaining disks or collars 34 and 35, carried by the spindle at either end of the sleeve. The upper end of the sleeve 32 is provided with a handle 15 36 or crank-arm, which when turned rotates the sleeve and driving it up or down in its bearing 33, and thus causing it to carry with it the spindle 20 and broom secured at the bottom of the same. In this way, therefore, 20 as the broom wears away it can be lowered by simply turning the crank-arm 36 in the proper direction; or, in case it be desirable, the broom can be raised entirely from the ground by turning the crank-arm in the reverse direction. It is apparent that were the spindle 25 20 (which constitutes in effect the axis of the rotating broom) inclined simply forward the broom would sweep the dirt lying directly in front of the same. If it were inclined laterally 30 only, that is, to the side of the frame and the driving-wheels carried by it, the broom would sweep the dirt lying on the side thereof; but with the present diagonal inclination of the spindle the broom sweeps not only the dirt 35 lying in front of it, but also that on the side thereof, producing thus a maximum efficiency for the sweeper and making the same particularly effective in the sweeping of gutters and similar places.

40 In Fig. 6 I have shown a double arrangement of the broom, the brooms being located at the opposite diagonal sides of the frame, and being each operated from the driving-wheels in the manner described in connection 45 with Figs. 1 to 5, inclusive. This last modification can of course be used in sweeping the street proper in addition to the gutter.

Having described my invention, what I claim is—

50 1. In a street-sweeper, a suitable frame, a

spindle carried by the same, a broom at the lower end of the spindle; a bracket for retaining said spindle in proper position on the frame, a rotatable sleeve loosely embracing the spindle, and suitable connections between the spindle and sleeve for varying the elevation of the spindle upon rotation of the sleeve in proper direction, substantially as set forth.

2. In a street-sweeper, a suitable frame, a spindle carried by the same and normally inclined both to the general plane of the frame and to the plane of rotation of the driving-wheels, a broom at the lower end of the spindle, a bracket for said spindle for retaining the latter at the proper inclination, a rotatable sleeve carried by said bracket loosely embracing the spindle, the sleeve supporting the upper end of the spindle and suitable connections between said spindle and sleeve for varying the elevation of the spindle upon rotation of the sleeve in proper direction, substantially as set forth.

3. In a street-sweeper, a suitable frame, a spindle carried by the same, a broom at the lower end of the spindle, a suitable bracket for retaining the spindle inclined to the general surface of the frame, an interiorly-screw-threaded bearing forming a part of said bracket, a sleeve exteriorly screw-threaded embracing the spindle and operating within the interiorly-screw-threaded bearing of the bracket, retaining-collars carried by the spindle at either end of the sleeve, a suitable crank-handle for imparting rotation to said sleeve and thus varying the position of the spindle, a pinion feathered to said spindle, a tubular extension for said pinion embracing the spindle, suitable boxing for said extension, a transverse shaft carried by the frame and having a terminal pinion coöperating with the pinion feathered to the spindle, and means for imparting rotation to said shaft from the driving-wheels of the machine, substantially as set forth.

In testimony whereof I affix my signature in presence of two witnesses.

HENRY MUELLER, JR.
